UNITED STATES PATENT OFFICE.

CHARLES V. CRULL, OF WASHINGTON, IOWA, ASSIGNOR TO WESTERN HOG OILER COMPANY, INC., OF WASHINGTON, IOWA, A CORPORATION OF IOWA.

HOG-WATERER.

1,319,567.

Specification of Letters Patent. Patented Oct. 21, 1919.

Application filed May 3, 1919. Serial No. 294,507.

To all whom it may concern:

Be it known that I, CHARLES V. CRULL, a citizen of the United States of America, and a resident of Washington, county of Washington, and State of Iowa, have invented certain new and useful Improvements in Hog-Waterers, of which the following is a full and clear specification.

This invention relates to that type of animal drinking fountain or trough in which an overhead supply-tank is employed, this tank being so arranged with respect to the drinking-bowl or trough that, as the water is removed from the latter, an additional supply will be delivered thereto from the supply-tank to maintain the level of the water in the drinking-trough at a predetermined point, the feed of the water taking place in accordance with the well-known hydrostatic law, as more fully hereinafter set forth.

In the drawings—

Figure 1 is a vertical sectional view; Figs. 2 and 3 are horizontal sectional views taken on lines 2 and 3, respectively, of Fig. 1.

Referring to the drawings by reference-characters, *a* designates a circular drinking-pan or trough which is supported at its annular edge on a cylindrical casing *b*, this casing being provided with a bottom-plate *c* which, together with the trough, forms a lamp-receiving chamber, the lamps being designated by the letters *d*. The vertical wall *b* and the drinking-trough are supported by a series of vertical wooden posts *e* beveled at their upper ends to fit against the tapered side-wall of the trough.

Supported upon the pan is a water-supply tank *f* annular in cross-section at its upper part and provided at its lower part—that is, in the zone adjoining the drinking-fountain—with a pair of oppositely-arranged indentations *g* into which the animals may insert their heads when they reach into the trough to drink therefrom. Surrounding the tank *f* is a jacket *h* which forms virtually an extension of the lower casing wall *b* and which forms, in conjunction with the wall of the tank, a warm-air space. To permit the heated air from the heating chamber below the trough to ascend into the space between the jacket and the tank-wall, I provide the annular drinking-trough with a series of vertical flutes *i* to form vertical

flues leading from the heating chamber into the jacket space. Coincidental with each of the drinking pockets *g*, there is provided a shield *j* which extends inwardly and bridges the heating jacket space, so as to thereby prevent the heated air and products of combustion from escaping at these points. These shields *j* are fastened to the wall of the jacket *h* and extend inwardly into each of the recesses *g*.

The jacket edge is provided with a top-plate *k* which at its center is provided with an opening which is adapted to be closed by a suitable pivoted plate *l*, the edge of this opening being provided with a depending flange *m* which engages over an upstanding flange *n* carried by a top-wall *o* covering the top of the supply-tank *f*. The height of the supply-tank *f* is such that an annular space is provided between its top-wall *o* and the top-wall *k* of the jacket, and it will be observed that the two flanges *m* and *n* form a division wall or baffle-plate between the heating-space and the central opening in the top-plate.

The top-wall *o* is dished downwardly to form in effect a funnel, the apex of which is connected to the upper open end of a vertical filling-tube *p*, whose upper end is protected by a piece of wire gauze *q* to prevent foreign bodies entering the filling-tube. Inside of the annular flange *n* on the top-wall is provided a petcock *r*.

Depending centrally from the bottom-wall of the supply-tank is a tube *s* open at its upper end to the water in the tank and partly closed at its lower side by a cap-plate *t*, this tube *s* being of such length that it depends into the water confined in the drinking-trough. The filling-tube *p* extends down into this tube to a point in close proximity to the cap *t*. The cap *t* is provided with a hole in its center and surrounding this hole is a depending flange *u* which forms a conical valve-seat; and adapted to seat against this valve-seat is a conical valve *v* affixed to the lower end of the rod *w* which extends up through the filling-tube and is provided with a handle *x* at its upper end which lies in the funnel-chamber so as to be conveniently reached when the top-plate *l* is slid to one side. The valve-rod is provided with a stop-button *y* which, when the valve is open, rests upon the gauze disk *q*.

It will be observed that when the lamps

or other heating devices are in use, the hot air and products of combustion will keep the water in the pan warm as well as the water in the supply-tank, and thus prevent freezing in cold weather. When the water rises in the pan, it seals the lower end of the discharge-tube *s* and thus prevents any more water flowing into the pan from the supply-tank, in accordance with the well-known hydrostatic law. As the water in the drinking-trough is removed, additional water will flow therewith from the supply-tank, so as to thereby maintain the level in the drinking-trough at the desired predetermined point. When it is desired to refill the supply-tank, the valve *v* is closed by pulling-up on the rod *w*, then the petcock *r* is opened, and the additional water poured into the central funnel-chamber. When the desired quantity of water is thus poured into the tank, the petcock *r* is closed and the valve *v* is opened, whereupon the normal automatic feed is again put into action. Surrounding the depending discharge-tube *s* is a cylindrical wall *z* which is affixed air-tightly to the bottom of the tank and depends into the water space of the trough, thereby forming an annular air-tight chamber whose lower end is open to the water in the trough, so that, as the water fills the trough, it will rise in this annular chamber and compress the air trapped therein. The air thus trapped forms an annular insulating body around the discharge from the water-tank. At this point the water in the discharge from the tank is subjected to the atmospheric temperature because of the drinking pockets *g*. In cold weather, the air at atmospheric temperature entering through the drinking pockets *g* would come in contact with this comparatively narrow column of water, which would, therefore, be likely to become frozen. By providing the annular wall or flange *z* by which the body of air is trapped, a dead-air or insulating medium will be provided around the discharge opening to protect the same.

It will be observed that a feature of im-

portance in my apparatus is that the operation of filling the supply-tank may be entirely controlled from the upper end of the tank, thereby avoiding the necessity of the attendant putting his hands down in the water in the trough, an operation which is inconvenient, especially in cold weather. This is accomplished by not only providing a filling-funnel and filling-tube, but also by arranging the discharge-valve *v* so that it may be operated from the top of the apparatus.

The nature and scope of the invention having been thus indicated and its preferred embodiment having been specifically described, what is claimed as new is:

1. In combination with a trough and a supply-tank surmounting same, a jacket surrounding the supply-tank and means for heating the air between the jacket and the tank, said tank and said jacket being provided with separated top-plates, annular flanges on said top-plates, said flanges co-operating to form the side-wall of a filling-funnel, said top-wall of the supply-tank inclining downwardly and inwardly in substantially the form of a funnel toward a central filling opening.

2. In an apparatus of the class set forth, a drinking-trough, an overhead supply-tank having a discharge end extending into the water-space of the drinking-trough, a filling-tube extending down through the supply-tank, a conical top-plate for said tank surrounding said filling-tube, an annular flange extending upwardly from said top-plate, a top-plate for said jacket, and a flange depending from said jacket top-plate and co-operating with the aforementioned flange and the tank top-plate to form a funnel for directing the water into the filling-tube, as and for the purposes set forth.

In testimony whereof I hereunto affix my signature.

CHARLES V. CRULL.
